UNITED STATES PATENT OFFICE

2,556,003

WATER GLASS AND CUP WASHER

George E. Sandell and Beatrice E. Sandell,
Hollywood, Calif.

Application June 11, 1948, Serial No. 32,304

2 Claims. (Cl. 51—185)

1

This invention relates to water glass and cup washers and more specifically to a new and improved scouring, washing and/or cleansing agent as exemplified in an optionally portable apparatus which may be positioned in a sink or the like and over which specific embodiment water glasses and cups may be nestingly forced and turned for cleaning their interior surfaces.

Prior art devices of the general character intended have been made in the form of bristled brushes and the like with or without means for forcing streams of water into the interior of the cups or glasses to be cleaned. The cleansing effect of such prior art devices has not been satisfactory because a desired pumping action or replenishment of wash water whether soapy or otherwise has not taken place nor has the entire interior surface been properly scoured or even contacted by the bristled or other washing surfaces. Moreover, in washing glasses of different diameters and shapes, suitable conforming adaptation of the adjacent washing surfaces to the washed surfaces has not taken place.

It is therefore an object of this invention to provide a new and improved washing element, as most desirably embodied in a water glass and cup washer, the latter being of simple construction, minimum number of operative parts, and susceptible of economical mass production.

Another object of this invention is to provide a new and improved water glass and cup washer having improved optionally replaceable operative parts.

Another object of this invention is to provide in a water glass and cup washer a new and improved automatic pumping action for wash water to a source of which the device may be connected or into which it is designed to be permanently or temporarily positioned.

It is another object of this invention to provide new and improved scouring and cleansing means for glasses, cups, and other household uses in combination with an appropriate abrasive and/or emulsifying agent.

Another further object of the invention is to provide new and improved supporting means for a water glass and cup washer of the desired character described.

Another specific object of the invention is the provision of a cleansing agent and means of improved construction and composition.

It is also among the objects of this invention to provide improvements in shape, construction and composition over prior art devices and materials generally intended to accomplish a similar purpose.

2

With these and other objects in view, the invention consists in the construction, arrangement and combination of the various parts of the device whereby the objects contemplated are attained, as hereinafter set forth, pointed out in the appended claims and illustrated in the accompanying drawing.

In the drawing:

Figure 1 is a vertical elevational view, partially in section, of a preferred embodiment of a water glass and cup washer illustrative of this invention.

Figure 2 is an elevational view of the same as used.

Figure 3 is a vertical elevational view, partially in section, of another preferred form of the invention as disposed in a sink or other basin of water for use.

Figure 4 is a vertical elevational view, parts being cut away, of a still further modified form of the invention.

Referring more particularly to the drawing and directing attention first to Figures 1 and 2, there is disclosed, by way of illustration but not of limitation, a water glass and cup washer generally designated by the numeral 5.

A washing element 10 made preferably of sponge rubber—optionally provided with a concavity 10a on its top surface and sloping sides 10b generally defining a truncated conical shape having a base 10c—may be fitted with an axially disposed sleeve 11 extending well into the body of the sponge material 10. The sleeve may make a removable connection, e. g., threaded, with a stud 12, the latter comprising an axial extension upon a vertical shaft or arm 13 as shown.

A washer 14 extends radially from the arm 13 providing a support for the base 10c of the sponge 10. For such purpose the arm 13 may be formed with a shoulder 15 against which the washer 14 is held when the sponge 10 is threaded to a fullest extent on the stud 12.

The sponge 10 may be bonded in any well-known manner as by cement to the sleeve 11 throughout the external or common surface 15a of the sleeve 11 and sponge 10 and may thereby made replaceable so that separate units of the sponge 10 and its optionally integral sleeve 11 may be substituted or replaced upon the arm 13 and washer 14.

The arm 13 may be formed with thread 16 at its lower end for connection with corresponding thread 17 formed in a boss 17a provided as on a suction cup 18. The boss 17a as shown may be made of rubber continuous with the main body of the suction cup 18 or the same may be formed

of more rigid material such as wood, plastic, metal, or the like, into which the lower end of the arm 13 may be threaded. In that case, such different material would necessarily be bonded in a manner known to those skilled in the art to the rubber portion of the suction cup 18.

In order to facilitate removal of the suction cup 18 when the same is in an operative position, a suitably shaped ear 19 is positioned at the periphery 19a, which when lifted will break the vacuum of the cup 18.

In its use as a water glass or cup washer, the glass or the like 20 is forced over the sponge cleaning element 10 as illustrated in Figure 2 until the bottom inside portion 22 of the glass contacts and compresses the concave upper end 10a of the sponge 10. In this position the annular lip 10d is firmly pressed against the inner corners 22a within the bottom of the glass and is compressed thereby so that upon slight rotation of the glass relative to the sponge a very effective wiping and optionally abrasive and cleansing action is secured. Simultaneously the axial downward movement of the glass 20 over the tapered side 10b of the sponge compresses the latter against the inner walls 21 of the glass for the full depth thereof.

The sponge should be formed of a sufficiently large diameter so that glasses of conventional size are automatically cleansed by the tapered sides of the sponge from the mouth or rim 22b of the glass to the bottom 22 thereof.

An examination of Figure 2 will disclose that the sponge has been compressed so that marginal edge portions 22c comprising portions of the tapered wall 10b as well as the bottom edge or base 10c of the sponge are normally depressed downwardly below the flange 14. Thus, the ordinarily tapered inside of the glass 20, the sleeve 11, and the supporting flange 14, provide surfaces between and against which a considerable amount of compression is given the sponge 10. This action may be utilized in the manner of a pump as will be most apparent from a consideration of the embodiment of Figure 3.

In Figure 3 a sponge 10 having a concave upper end 10a and tapered sides 10b may form a substantially truncated cone. The cleansing element thus provided may be positioned on a suction cup 18a optionally formed with an ear 19a by which the same may be removed in a manner similar to that described in connection with Figures 1 and 2 of the first preferred embodiment.

An arm or shaft 25 formed with an axial passage 26 therein may likewise be formed with an integral radially extending supporting flange 27. All supporting structure for the sponge, in the form of Figure 3, including the radially extending flanges 27 and their upturned marginal edges 29, the upper end 29a of the arm 25 including said arm, and the suction portion 18a and ear 19a, may similarly be molded integrally from relatively hard rubber or analogous resilient material.

Flow through the passage 26 may be controlled by a check valve 30 and for such purpose may be provided with a lateral passage 31 communicating as by means of a restricted port 32 with the outside at a point adjacent the suction cup base 18a. A seat 33 for a ball valve 34 may be thus provided and a coil spring 35 may normally urge the same against said seat 33 to close said port 32.

Inasmuch as the device as embodied in Figure 3 is designed to be positioned within a sink or other container 32a, the water 36 normally contained therein should be maintained at a level

above the port 32. A pumping action by the sponge 10 during the normal use of the device, as hereinabove set forth, is occasioned by the intermittent compression and expansion thereof during use. Thus, when a glass is pressed downwardly over the sponge, any water within the same will be squeezed out and will drain out of the glass between the sponge and the interior wall of the glass, being prevented from return by way of the passage 26 to the source 36 because of the check valve 30. On the other hand, wash water 36 is drawn through the port 32 and the passage 26 into the sponge 10 during the expansive movement of the sponge as when a glass is removed therefrom. In this manner water is continually and automatically refreshed and replenished in the sponge 10 by a pumping cycle, i. e., via the port 32, the passage 31, the passage 26, the sponge 10 and (through compression of the sponge by the glass, etc.) back from the glass to the source 36.

Manifestly, in lieu of the suction cup 18 of Figures 1 and 2 or the suction cup 18a of Figure 3, any other suitable supporting member may be provided whether temporary or permanent. And while in the forms under consideration the device is normally caused to adhere to the surface 37 or bottom 37a of a drain board or wash basin, respectively, the same may likewise be caused to extend horizontally from a vertical wall. In such case, in the form of Figure 3 (unless the sponge support is modified in an obvious manner as by an auxiliary conduit) the device would lose its desired pumping effect.

Therefore, it is also within the contemplation of this invention to provide a direct connection with the passage 26 by a pipe leading to a customary water supply under pressure whereby fresh water may be continuously passed into and through the sponge 10 to supply fresh water to the glasses, cups, etc., as they are cleansed thereby.

Aside from its highly satisfactory properties as a cleansing agent, per se, sponge rubber, whether natural or synthetic, provides an admirable matrix for abrasive or scouring material such as rotten-stone, chalk, rouge, opal, putty-powder, pumice, and the like, whether in dust or cellular form. These abrasive materials may if desired, be embodied in a scouring soap of well-known composition. Such scouring agents, either with or without added soap, may be directly mixed with a raw or uncured rubber material of which the sponge is to be manufactured prior to molding or cutting the desired sponge into its finished form. By this technique, substantially any amount, as approximately 10 to 50 percent, of the weight or bulk of the cleaning element 10 may comprise a detergent or an abrasive or any combination or part percentage of these. Obviously, an increase in the amount of abrasive or soap will increase the rigidity of the element 10. Moreover, the density of the sponge rubber may be varied as desired either together with the proportion of scouring or abrasive material or independently to provide a scouring pad or element of suitable firmness for any intended use.

As noted, utilization of sponge or even solid rubber, whether natural or artificial, as a matrix and carrying agent for a detergent and/or scouring materials, while particularly adapted for use in a water glass and cup washer as herein illustrated, is conceived of as an essential portion of the novelty of the instant invention and it is contemplated that whether used in the form of

a glass cleaner or as a scouring agent in the form of a scouring pad of any shape, round, square, oblong, flat, discoid, or the like, may be made and used separately.

The element 10, of Figures 1 and 2 in particular, may be replaceable in sponges of varying degrees of hardness and having any desired amount of scouring agent or detergent embodied therein. Such detergent or scouring agents may be concentrated on the periphery of the sponge or may be uniformly distributed therethrough, or they may be distributed thereon or therein in any other manner, as by concentrating the soap in the center and the scouring agent at the surface. If uniformly distributed, the soap to some extent and the scouring agent ordinarily to a greater extent, will become exposed by attrition of the sponge, being more or less sealed in the body or cells of the rubber until such time.

The further modified form of Figure 4 in most respects resembles the form of Figure 1, parts corresponding thereto being therefor similarly numbered, except for the permissible optional omission of the rim 10d of Figure 1 and of the similar optional omission of the washer 14. The embodiment of Figure 4 features a ball 50 on the lower end of the stem 13 slidably insertable into or removable from a suitable socket 51 formed in the rubber body of the suction cup 18.

Thus, by grasping the handle 13 the same may be axially removed from the socket 51 whether the latter is operatively in place or not and may be either permanently or temporarily utilized in such removed condition as for washing the rims of glasses or forcibly thrusting the same axially into a glass or the like for washing the latter in a manner similar to that heretofore set forth in connection with the description of the previous embodiment.

In the event that the suction cup 18 is retained in its adherent relationship to the surface 37, the neck 52 of the shaft thereby bearing on corresponding shoulders 53 of the suction cup there-adjacent serves to maintain the stem 13 in a desired attitude of extension which is sufficiently rigid for normal use of the apparatus first described inasmuch as the principal force exerted upon the sponge 10 is in an axial direction.

If desired and to prevent rotation of the sponge on its axis when a glass or cup is turned thereon, the ball 50 may be made elliptical in form or may have other irregular cross-sectional configurations, and the socket 51 may be correspondingly shaped to suit in order that the member 50 will not rotate within the socket 51, although it is susceptible of axial removal and insertion as by temporary distortion and spreading of the shoulders 53.

This invention features the provision of a new and improved glass and cup washer as embodying a new and improved cleansing and scouring element either usable with an appropriate framework as described or independently thereof.

It is therefore within the contemplation of this invention, as stated, to provide a new and improved scouring means for general household cleaning.

Likewise featured by this invention is a new and improved means for conducting wash water

with or without a detergent dissolved optionally therein automatically through a cleaning and scouring element as described to a point of use.

Although the invention has been herein shown and described in what is conceived to be the most practical and preferred embodiment, it is recognized that departures may be made therefrom within the scope of the invention which is not to be limited to the details disclosed herein but is to be accorded the full scope of the claims so as to embrace any and all equivalent structures. Thus the terms "rubber," "sponge" or "sponge rubber" as herein used are intended to denote plastic materials such as plastic foam, Vinylite and other materials of readily deformable and resilient quality.

The invention having been herein described, what we claim as new and desire to secure by Letters Patent is:

- 20 1. A water glass and cup washer comprising a main base, an arm extending from said base, a sponge rubber cleansing body of substantially truncated conical shape co-axially mounted upon the end of the arm distal from said base, and a radially extending resilient flange on said arm as and for a support for said sponge body, said flange being co-extensive with the base of said truncated conical body and composed of relatively harder rubber.
- 25 2. A water glass and cup washer comprising a main base, an arm extending from said base, a sponge cleansing body mounted upon the end of the arm distal from said base, said arm defining a conduit communicating between the interior of said cleansing body at a point adjacent said main base, and a one-way valve in said conduit permitting a flow of wash water at said base into said sponge body in response to successive forced compressions and normal re-expansions of said sponge body as used.
